UNITED STATES PATENT OFFICE.

BYRON T. SEELYE, OF CHICAGO, ILLINOIS.

AIR-CHECK FOR VOTING-MACHINES.

SPECIFICATION forming part of Letters Patent No. 777,150, dated December 13, 1904.

Application filed April 15, 1904. Serial No. 203,283. (No model.)

To all whom it may concern.

Be it known that I, BYRON T. SEELYE, a citizen of the United States, residing at 333½ Flournoy street, city of Chicago, and State of Illinois, have invented certain new and useful Improvements in Air-Checks for Voting-Machines, of which the following is such a full, clear, and exact description as will enable others skilled in the art to which it appertains to make and use my said invention.

My invention relates to voting-machines of that type which employ sliding perforated dropping slides to deposit balls in underlying ballot-boxes. Machines of this type are ordinarily constructed and arranged so that the voter may operate a single lever to simultaneously move all of the slides outward into position to be adjusted by the voter as he may desire during the operation of voting and so constructed and arranged that the judges of the election may by operating a single lever simultaneously move all of the slides rearwardly into position for use by the next succeeding voter. In practice it is found that in the hurry incident to voting the voter is very likely to move the lever too quickly, thereby causing undue concussion of the parts and unnecessary strain on the mechanism.

The purpose of my invention is to provide an air-cushion housed within the cabinet of the voting-machine and adapted to prevent too sudden movement and undue concussion and strain of the mechanism during the simultaneous outward movement of all of the slides.

With this purpose in view my invention consists in the novel features of construction and combinations of parts shown in the annexed drawings, to which reference is hereby made, and hereinafter particularly described, and finally recited in the claims.

Referring to the drawings, Figure 1 is a perspective view of a voting-machine embodying my improvements and shows only such operative parts of the machine as are necessary to illustrate the connection of my improved air-check with the machine. Fig. 2 is an enlarged vertical section on the line 2 2 of Fig. 1. Fig. 3 is an enlarged longitudinal vertical section taken on the axis of the air-

cylinder, and Fig. 4 is an enlarged partial vertical section on the line 4 4 of Fig. 1.

Similar reference-letters designate like parts in all of the views.

The main structure of the machine consists of a cabinet A. Perforated slides B are slideable in the cabinet between guides B', and the perforations in the slides are registerable with suitable openings in ball-boxes C underlying the slides. Horizontal longitudinal shafts D are mounted to turn in the cabinet. Toothed segment-wheels D', secured on the shafts, engage with the teeth of rack-bars E, which are horizontally slideable between suitable guides E' on the cabinet. A cross-bar F connects the rack-bars E and engages with upwardly-projecting pins b on the slides B, respectively, to move all of the slides simultaneously outward. Levers G are connected with the shafts D by screws g', screwing into the ends of the shafts, so that the levers may be detached for convenience in transportation. An arm G', having at its lower end a slot g, is secured on the shaft D by a set-screw g².

A cylinder H is mounted to oscillate on a stationary block H', secured in suitable position inside of the cabinet. Near the closed end of the cylinder H is a suitable valve h, permitting gradual escape of air from the cylinder.

A piston H² is secured to a rod H³, which is connected with the lower member of the arm G' by a pin h', sliding in the slot g. The rod H³ slides in a suitable gland in a diaphragm h² near one end of the cylinder H. A coiled spring H⁴ surrounds the rod H³. One end of the spring H⁴ abuts against a nut h⁴, screwing into the diaphragm h², and the other end abuts against a collar h³ on the rod H³.

The operation of the device is as follows: When it is desired to move all of the slides simultaneously outward, it is only necessary for the voter to pull on the upper end of the front lever G, thereby turning the front segment-wheels D' so as to move the rack-bars 95 forwardly and cause the cross-bar to engage with the pins on the slides and move all of the slides simultaneously outward. When the

front lever G is pulled forward or the rear lever G is pushed rearward, the piston H² travels rearward in the cylinder, cushioning the air in the cylinder until it gradually escapes through the valve h, thereby preventing too rapid movement of the lever and the slides.

The spring H⁴ also serves as a cushion and permits the use of a shorter cylinder and greater movement of the lever than could be obtained if a cylinder and piston alone were used, as in that case it would be necessary to employ a cylinder of inconvenient length. The spring also reacts and assists in retracting the piston and restoring the lever to its initial position.

Having fully described my invention, what I claim as new, and desire to secure by Letters Patent, is—

1. In a voting-machine, the combination of a cabinet, dropping slides slidable in said cabinet, means for simultaneously moving all said dropping slides outward, an oscillative air-cylinder having a valve, a piston slidable in said cylinder, and a connecting-rod connecting said piston with the means for operating said slides, as set forth.

2. In a voting-machine, the combination of a cabinet, a shaft turnable in said cabinet, toothed segment-wheels on said shaft, rack-

bars operative by said segment-wheels, a cross-bar connecting said rack-bars, dropping slides operative by said cross-bar, an oscillative air-cylinder having a valve, a lever secured on said shaft, a piston slidable in said cylinder, a rod connecting said piston with said shaft, and a spring acting to retract said piston, as set forth.

3. In a voting-machine the combination of a cabinet, a shaft turning in bearings on said cabinet, a lever fitting on the end of said shaft, a securing device connecting said lever with said shaft, segment-wheels secured on said shaft, rack-bars meshing with said segment-wheels, slides slidable in said cabinet and having upwardly-projecting pins, a cross-bar connecting said rack-bars and engaging with the pins on said slide, an arm secured on said shaft, a cylinder mounted to oscillate in said cabinet, and a piston working in said cylinder and connected with the arm secured on said shaft, as set forth.

In witness whereof I have hereto subscribed my name, at Bloomington, Illinois, this 8th day of April, 1904.

BYRON T. SEELYE.
